Attorney.

UNITED STATES PATENT OFFICE.

EARL PAGETT, OF PERU, KANSAS.

STRINGED MUSICAL INSTRUMENT.

Application filed April 21, 1925. Serial No. 24,758.

This invention relates to stringed musical instruments of the violin type; and it consists in combining a horn, for directing and amplifying the sound waves, with a sound box having vibrating diaphragms under the strings, as hereinafter fully described and claimed.

In the drawings, Figure 1 is a side view of a stringed musical instrument constructed according to this invention. Fig. 2 is a side view, drawn to a larger scale, showing the sound box partially in section. Fig. 3 is a plan view of the sound box from below.

15 The instrument is provided with a tuning head 6, a neck, and a finger-board 7, similar to those of a violin. The body 8 of the instrument at the other end of the finger-board from the tuning head has a conical sound collecting chamber 10. A horn 12 of approved tapering shape and proportions has its smaller or inlet end 14 connected to the apex of the chamber 10 in line with its axis. The horn is curved around so that 25 its bell 15 projects over the strings 16 of the instrument. A tail-piece 17 is secured to the horn, and the strings are strung between this tail piece and the pegs of the tuning head. The strings are preferably five in 30 number, and are tuned in the same manner as violin strings. The bell and the larger part of the horn are preferably formed of trumpet brass, and are provided with a slip joint 18 for convenience in carrying the instrument. The remainder of the horn and 35 the body of the instrument are preferably formed of cast aluminum, but they may be formed of any other suitable material which is light and strong.

40 A sound box 20 is mounted over the large end of the sound collecting chamber 10, and can be secured to the body by screws or other fastening devices. A bridge 21, similar to a violin bridge, rests on the upper diaphragm 22 of the sound box and supports 45 the strings. The lower diaphragm 24 of

the sound box is similar to the upper diaphragm but has outlet openings 25 for the sound waves of any suitable size and shape. A sound post 26 is inserted in the sound box 50 between the two diaphragms, and preferably is arranged under one leg of the bridge. The sound box is preferably made of wood similar to that used in making violins. The instrument is preferably played with a violin 55 bow, but it may be played by plucking the strings.

The quality of tone is similar to that of a violin, but is very clear and penetrating. The quality of tone can be varied by changing 60 the material of the diaphragms, and metallic diaphragms can be used to advantage.

What I claim is:—

1. A stringed musical instrument, comprising a body provided with a tuning head, a conical sound collecting chamber, and a horn arranged in line with the tuning head on the longitudinal center line of the instrument extending through the tuning head, 65 finger board and the center line of the conical chamber and connected to the smaller end of the conical chamber; a sound box mounted on the body over the large end of the conical chamber and provided with a diaphragm, a bridge resting on the diaphragm, and a string strung over the bridge between the tuning head and the horn, and attached 70 to the latter.

2. A stringed musical instrument as set 80 forth in claim 1, the said horn having a detachable bell which projects on the other side of the string from the body and sound box.

3. A stringed musical instrument as set 85 forth in claim 1, the said body, tuning head and conical sound collecting chamber being formed integral with each other and of metal.

In testimony whereof I have affixed my signature.

EARL PAGETT.
